Richard H. Benner, Greene County, Ohio
(7655 Wilmington Pike, Dayton, Ohio)

Filed Apr. 15, 1960, Ser. No. 60,330

Term of patent 14 years

(Cl. D13—1)

FIG.1

The essential features of my design reside in the portions shown in full lines.

This application is a continuation-in-part of my co-pending application Serial No. D. 53,657, filed December 5, 1958.

I claim:

The ornamental design for an outdoor drive by food market sales building, substantially as shown and described.
